(57) **CLAIM**

The ornamental design for a camera tripod mount, as shown and described.

DESCRIPTION

FIG. 1 is a front, bottom, and right perspective view of a camera tripod mount in an expanded configuration;

FIG. 2 is a rear, top, and left perspective view thereof;

FIG. 3 is a rear view thereof;

FIG. 4 is a front view thereof;

FIG. 5 is a right view thereof;

FIG. 6 is a left view thereof;

FIG. 7 is a top view thereof;

FIG. 8 is a bottom view thereof;

FIG. 9 is a front, bottom, and right perspective view of the camera tripod mount in a folded configuration;

FIG. 10 is a rear, top, and left perspective view thereof;

FIG. 11 is a rear view thereof;

FIG. 12 is a front view thereof;

FIG. 13 is a left view thereof;

FIG. 14 is a right view thereof;

FIG. 15 is a top view thereof; and,

FIG. 16 is a bottom view thereof.

The broken lines in the drawings illustrate portions of the camera tripod mount in which the design is embodied and form no part of the claimed design.

1 Claim, 16 Drawing Sheets
